UNITED STATES PATENT OFFICE.

CHILTON WITHERS BLUE, OF MONTGOMERY, ALABAMA, ASSIGNEE TO JANNEY & COMPANY, OF MONTGOMERY, ALABAMA.

Brake-Shoe.

1,153,753.

Specification of Letters Patent. Patented Sept. 14, 1915.

Application filed April 22, 1913. Serial No. 762,792.

To all whom it may concern:

Be it known that I, CHILTON WITHERS BLUE, a citizen of the United States, and a resident of Montgomery, in the county of 5 Montgomery and State of Alabama, have invented an Improvement in Brake-Shoes, of which the following is a specification.

My invention is an improvement in that type of brake-shoes for railway rolling- 10 stock in which a body or wear portion is cast upon a comparatively thin back formed of steel, or other wrought metal, and serving as a reinforce for the body.

My invention is embodied in the particular 15 construction of the reinforce and its connection with the wear block or brake shoe in such manner that it cannot become disconnected from the latter.

In the accompanying drawing Figure 1 is 20 a perspective view of the shoe. Fig. 2 is a perspective view of the back of reinforce, together with a wrought-metal staple used to reinforce the back lug with which brake-shoes are commonly provided. Fig. 3 is a 25 transverse section on the line 3-3 of Fig. 1. Fig. 4 is a cross section on the line 4-4 of Fig. 1.

The numeral 1 indicates the cast-iron body 30 of the shoe, 2 the steel back or reinforce therefor, and 3 a wrought iron U-shaped device, or staple, that serves as a reinforce for the perforated lug which is usually cast on the back of the body of a brake-shoe, and which serves for attachment of the 35 latter to a cross-bar or other support. The straight parallel legs of the device 3 are provided with lateral projections in the nature of teeth, which assist in holding the device firmly connected with the cast metal 40 body.

The reinforce 2 is a moderately thin, steel plate having its side edges bent inward and each provided with a series of recesses 4 and intervening dove-tailed hooks, or claws, 5. 45 The said recesses and hooks are formed in those portions of the reinforce which intervene the ends and the middle of the plate.

In consequence of the inward or downward bend of the hooks thus formed, they are completely embedded in the block or shoe 1, 50 as shown in Fig. 4, and experience has demonstrated that the reinforce cannot be detached from the block, which sometimes occurs in cases where the reinforce is flat and is partly embedded in the top or face of 55 the block or shoe. The middle portion is provided with elongated slots 6 arranged parallel to the side edges 5^a. This middle slotted portion of the reinforce is thus left the full width of the plate, so that the reinforce 60 is not weakened at that point, as usual in other brake-shoes of this type. The hooks or claws 5 are widest at their outer ends, thus forming sharp lateral projections, as shown in Fig. 2. The corners of the claws 65 thus approach each other, so that the distance between them is less than the width of the recesses 4 in the direction of the length of the reinforce. It is apparent that when the latter is cast in the block or body of the 70 shoe, as shown in Fig. 1, the hooks or claws 5 project down into the body and the cast metal fills the space between them, or, in other words, fills the recesses 4. The reinforce is thus made practically one with 75 the body, its outer side or back being flush with the body in which the claws and recesses are buried. It is obvious that the reinforce cannot be separated from the body, so that they form practically one piece or 80 block. The side edges 5^a of the middle portion of the reinforce are embedded in the body 1 to the depth of the thickness of the plate.

The legs of the reinforcing staple 3 pass 85 through the slots 6 in the middle portion of the reinforce 2, and are held in the position indicated in Fig. 3 when the body is cast. The legs of the staple are provided with lateral projections, as shown in Fig. 1, or 90 flattened and broadened, which effectually prevent withdrawal of the device from the body 1. The bowed outer end of the reinforce 3 projects far enough from the body

2
to leave an eye 7, as shown in Figs. 1 and 3, which provides for attachment to a support for the brake-shoe.

I claim:—

5 The improved brakeshoe comprising a cast metal body and a thin wrought metal reinforcing plate partly embedded in said body and flush with the back of the same, the

said plate having its side edges formed with the dove-tail hooks which are curved inward and downward, and embedded in the cast metal as described.

CHILTON WITHERS BLUE.
